[57] ABSTRACT

In an apparatus for winding yarn comprising means for holding a yarn package support onto which support the yarn is to be wound, a rotationally driven roller for engaging the surface of the yarn package support upon threading-up and thereafter the surface of the package of yarn being formed on the support thereby to define a nip with and rotationally to drive the yarn package support and the yarn package being formed thereon, a traverse guide for guiding the yarn to the nip whereupon the yarn is wound onto the package support, and means for reciprocating the traverse guide relative to the rotating package support thereby to distribute windings of the yarn on the package support, the improvement in which the traverse guide comprises means defining at least two surfaces for passage of the yarn in contact therewith in a zig-zag path, the traverse guide thereby being adapted to maintain the arrangement of a yarn fed thereto which yarn is constituted of a plurality of ends arranged in mutually parallel side by side relation.

APPARATUS AND METHOD FOR TREATING YARN

This is a continuation, of application Ser. No. 172,704 Filed Aug. 18, 1971, now abandoned.

This invention relates to improvements in conventional apparatuses and methods for winding yarn. More specifically, this invention relates to improvements in such apparatuses and methods to permit the winding of a yarn constituted of a plurality of ends arranged in mutually parallel side by side relation which winding takes place in such manner that the position of the ends relative to each other in the wound yarn is the same as in the unwound yarn.

Apparatuses for winding yarn are known which apparatuses comprise means for holding a yarn package support onto which support the yarn is to be wound, a rotationally driven roller for engaging the surface of the yarn package support upon threading-up and thereafter the surface of the package of yarn being formed on the support thereby to define a nip with and rotationally to drive the yarn package support and the yarn package being formed thereon, a traverse guide for guiding the yarn to the nip whereupon the yarn is wound onto the package support and means for reciprocating the traverse guide relative to the rotating package support thereby to distribute windings of the yarn on the package support. Such an apparatus is described, for example, in U.S. Pat. No. 3,345,003.

Such an apparatus may be employed to wind a yarn constituted of a plurality of ends arranged in mutually parallel side by side relation. In some instances it may be desired that the plural end yarn thus to be wound be of at least two different colors. For example, a heather yarn may be desired for carpeting. Though such a yarn may appear to involve a random intermingling of at least two colors, surprisingly it has been found that unless the relative positions of the ends which are combined are controlled, undesirable effects may result. This may manifest itself particularly pronouncedly when the yarn is tufted to form carpeting or other pile fabric. Rather than there being an even heather effect, different colors may predominate in various parts of the carpet.

According to the invention, it has been found possible so to guide the plural ends of yarn in mutually parallel side by side relation during the winding that they maintain the same positions relative to each other throughout the winding whereupon a predetermined arrangement of the yarns is maintained and a uniform heather effect is achieved.

According to one aspect of the present invention, the aforementioned traverse guide of the winding apparatus comprises means defining at least two surfaces for passage of the yarn in contact therewith in a zig-zag path, the traverse guide thereby being adapted to maintain the arrangement of the yarn fed thereto which yarn is constituted of a plurality of ends arranged in mutually parallel side by side relation.

The aforementioned type of winding apparatus, such as described in U.S. Pat. No. 3,345,003, may further comprise means for holding a second yarn package support in juxtaposition to the first yarn package support, a second rotationally driven roll for engaging the surface of the second yarn package support upon threading-up and thereafter the surface of the package of yarn being formed on the support thereby to define

a nip with and rotationally to drive the second yarn package support and the yarn package being formed thereon, a second traverse guide for guiding the yarn to the nip of the rotating second roll and rotating second package support, means for guiding the yarn to the second nip whereupon the yarn is wound on the second package support, means for reciprocating the second traverse guide relative to the second package support thereby to distribute windings for the yarn on the second package support, a change-over guide, means for moving the change-over guide from a first position for guiding the yarn to the first traverse guide to a second position for guiding the yarn to the second traverse guide, and means for guiding the yarn to the change-over guide.

According to another aspect of the present invention, the change-over guide and the second traverse guide each comprise means defining at least two surfaces for passage of the yarn in contact therewith in a zig-zag path, the means for guiding the yarn to the change-over guide and the second traverse guide each thereby being adapted to maintain the arrangement of the yarn fed thereto which yarn is constituted of a plurality of ends arranged in mutually parallel side by side relation.

Preferably, each of the surfaces of each of the aforementioned guides of the invention is defined by an elongated member oriented transversely of the path of the yarn in contact with the member.

The invention will now further be described by reference to a specific embodiment thereof, as illustrated in the drawings, in which:

FIG. 1 is an isometric view of the type of winding apparatus as described in U.S. Pat. No. 3,345,003 and incorporating an arrangement of yarn guides according to the present invention;

FIG. 2 is a schematic illustration of part of the apparatus of FIG. 1;

FIG. 3 is a plan view of one of the yarn guides of FIG. 1;

FIG. 4 is a front elevation of the yarn guide of FIG. 3;

FIG. 5 is a rear elevation of the yarn guide of FIG. 3;

FIG. 6 is an enlarged isometric view of one of the yarn guides of FIG. 1; and

FIG. 7 is an enlarged isometric view of another of the yarn guides of FIG. 1.

From the periphery of a toothed wheel 10, representing the setting zone of a drawing-stuffer box crimping apparatus of the type described in U.S. Pat. No. 3,454,998, is withdrawn a yarn 11 constituted of four ends arranged in mutually parallel side by side relation (FIG. 1). In this particular example, a first of the ends is red, a second is yellow, a third is brown and the fourth is orange and each of the ends is 150/6 (150 denier, 6 filament). The withdrawing of the yarn is effected by a counterclockwise driven rubber-surfaced roll 12 (FIG. 2) which forms a nip first with a yarn package support 13 mounted on a mandrel 14, upon threading-up, and subsequently with the yarn package 15 formed on the yarn package support (FIG. 1). It will be appreciated that surface engagement of the counterclockwise driven roll 12 drives first the yarn package support 13 and then the yarn package itself 15 in clockwise direction. The mandrel 14 is free to rise as the yarn package 15 builds. As seen in FIG. 1, there is actually a pair of yarn package supports 13 though only one

of them is visible and sequentially upon each is formed a respective yarn package 15.

From the toothed wheel 10 the yarn travels first between a pair of guide pins or pulleys 16 and 17, then through yarn guide 18, then through the eyelet 19a of a change-over guide 19 and then through traverse guide 20 or 20' to the nip between the roll 12 and the yarn package support 13 or the yarn package 15. It is readily apparent that the yarn guide 20' is a mirror image of the yarn guide 20.

In FIG. 1, since the arm 19b of the change-over guide 19 is cocked to the left, yarn is being wound on the left-hand package support. When a full package of yarn has formed on the left-hand package support, the change-over guide 19 will then be actuated to cock to the right to begin winding on the right-hand package support. In the meantime, the full package will be removed from the left-hand side of the apparatus and an empty package support placed on the left-hand side of the mandrel so that the apparatus will be ready for cocking of the arm 19b back to the left when the right-hand package support has been filled with yarn. In like manner, this switching back and forth may be continued indefinitely to provide continuous operation.

The yarn guide 18 is comprised of a back plate 18a and rods 18b and 18c (FIGS. 1, 7). It will be seen that the yarn guide thus formed is symmetrical so that each side of the yarn guide 18 is a mirror image of the other side so that the yarn is guided in the same fashion whether onto the left-hand package support or onto the right-hand package support. The rods 18a and 18b are so positioned that the yarn 11 travels a zig-zag path and the resultant tensioning of the yarn 11 across the surfaces defined by the rods 18b and 18c maintains the ends in their aforesaid mutually parallel side by side relation.

The yarn guide 20 is formed of a back plate 20a a side plate 20b and rods 20c and 20d. The guide 20' is correspondingly formed of a back plate 20'a, a side plate 20'b and rods 20'c and 20'd. In the back plate 20a is formed a notch 20e and in the back plate 20'a is formed a corresponding notch 20'e. It will thus be appreciated that the respective back plates 20a and 20'a with their respective notches 20e and 20'e correspond essentially to a conventional traverse guide. The rods 20c and 20d or 20'c and 20'd represent the modification according to the present invention which maintains the yarn during the traversing in the mutually parallel side by side arrangement of the ends. The rods 20c and 20d or 20'c and 20'd are so arranged that the yarn travels a zig-zag path in travelling in contact with surfaces defined by the rods. The resultant tensioning of the yarn in contact with the surfaces defined by the rods 20c and 20d or 20'c and 20'd maintains the ends in the aforesaid mutually parallel side by side relation. Hence, the arrangement of the ends in the yarn 11 is the same on the package 15 as it was when the yarn 11 left the toothed wheel 10.

The foregoing detailed description of the invention is an illustration of and not a limitation upon the scope of the invention as defined by the appended claims.

What is claimed is:

1. In an apparatus for winding yarn comprising means for holding a yarn package support onto which support the yarn is to be wound, a rotationally driven roller for engaging the surface of the yarn package support upon threading-up and thereafter the surface of the package

of yarn being formed on the support thereby to define a nip with and rotationally to drive the yarn package support and the yarn package being formed thereon, a traverse guide for guiding the yarn to said nip whereupon the yarn is wound onto the package support, means for reciprocating the traverse guide relative to the rotating package support thereby to distribute windings of the yarn on the package support, means for holding a second yarn package support in juxtaposition to the first yarn package support, a second rotationally driven roller for engaging the surface of the second yarn package support upon threading-up and thereafter the surface of the package of yarn being formed on the support thereby to define a nip with and rotationally to drive the second yarn package support and the yarn package being formed thereon, a second traverse guide for guiding the yarn to said nip of the rotating second roller and rotating second package support, means for guiding the yarn to the second nip whereupon the yarn is wound on the second package support, means for reciprocating the second traverse guide relative to the second package support thereby to distribute windings of the yarn on the second package support, a change-over guide, means for moving said change-over guide from a first position for guiding the yarn to the first traverse guide to a second position for guiding the yarn to the second traverse guide, and means for guiding the yarn to the change-over guide, the improvement in which the means for guiding the yarn to the change-over guide and the two traverse guides each comprise means defining at least two surfaces for passage of the yarn in contact therewith in a zig-zag path, said means for guiding the yarn to the change-over guide and the two traverse guides each thereby being adapted to maintain the arrangement of a yarn fed thereto which yarn is constituted of a plurality of ends arranged in mutually parallel side by side relation.

2. An apparatus according to claim 1 in which each of the surfaces of each of the second traverse guide and the means for guiding the yarn to the change-over guide is defined by an elongated member oriented transversely of the path of the yarn in contact with the member.

3. In a method for winding yarn, constituted of a plurality of ends arranged in mutually parallel side by side relation, onto a yarn package support, comprising rotationally driving the support by arranging the support in contact with a roller for engagement of the roller with the surface of the support during threading-up and thereafter with the surface of the package of yarn being formed on the support whereby the roller forms a nip first with the support and thereafter with the yarn package being formed on the support, guiding a yarn to the nip, rotationally driving the roller thereby to wind the yarn on the support and simultaneously reciprocating the yarn relative to the support thereby to distribute windings of the yarn on the support, guiding the yarn into engagement with change-over guide means for guiding the yarn alternatively to the vicinity of the first package support or to the vicinity of a second package support in juxtaposition to the first package support and for transporting the yarn therebetween, after the desired quantity of yarn has been wound on the first package support actuating the change-over guide means to transport the yarn to the vicinity of the second package support, rotationally driving the second support by arranging the second support in contact

with a second roller for engagement of the second roller with the surface of the second support during threading-up and thereafter with the surface of the package of yarn being formed on the support whereby the second roller forms a nip first with the second support and thereafter with the yarn package being formed on the second support, guiding the yarn to the nip of the second roller and second package support, rotationally driving the roller thereby to wind the yarn on the second support and simultaneously reciprocating the yarn relative to the second support thereby to distribute windings of the yarn on the second support, the improvement in which the guiding of the yarn into engagement with the change-over means and the guiding of the yarn to the two nips each comprise passing the yarn in a zig-zag path in contact with a plurality of surfaces thereby to maintain said arrangement of the yarn ends.

4. An apparatus according to claim 1, in which the change-over guide and the two traverse guides each comprise means defining at least two surfaces without interposition of surface-defining means between any pair of mutually parallel ends of which the yarn is comprised, each of said guides thereby being adapted to maintain said yarn arrangement solely by the tension imparted to the yarn by the passage of the yarn in contact with said at least two surfaces.
5. A method according to claim 3, in which each of the passings of the yarn in a zig-zag path in contact with a plurality of surfaces is conducted without interposition of surface-defining means between any pair of mutually parallel ends of which the yarn is comprised whereby the maintaining of said arrangement is solely by the tension imparted to the yarn by the passage of the yarn in contact with said at least two surfaces.
